[57] CLAIM

The ornamental design for a coffeemaker, as shown and described.

DESCRIPTION

FIG. 1 is a front perspective view of a coffeemaker embodying our new design;

FIG. 2 is a left side elevational view thereof;

FIG. 3 is a top plan view thereof;

FIG. 4 is a front elevational view thereof; and

FIG. 5 is a rear elevational view thereof.

The bottom of the coffeemaker is substantially plain and unornamented.
